UNITED STATES PATENT OFFICE.

ABRAHAM COOPER, OF BROOKLYN, NEW YORK.

LIGHTING-FIXTURE RING.

Application filed February 24, 1923. Serial No. 620,875.

To all whom it may concern:

Be it known that I, ABRAHAM COOPER, a citizen of the United States, residing in the borough of Brooklyn, county of Kings, city 5 and State of New York, have invented an Improvement in Lighting-Fixture Rings, of which the following is a specification.

My present invention relates to lighting fixtures and more particularly to that type 10 of lighting fixture consisting of a plurality of arms connected to a ring. Lighting fixtures of this type have been constructed heretofore, but so far as I am aware the ring member has been made as an integral 15 structure and has been connected to the several arms included in the fixture by suitable coupling members or otherwise, which latter members are adapted to receive and have attached thereto the sockets or other 20 devices to which the lighting members of the fixture are connected. In this type of fixture, therefore, in which the integrally constructed ring is employed the fixture obviously was not adapted to have the parts 25 disconnected so as to be packed in a relatively small space for shipping, storing, or other purposes. The object, therefore, of my present invention is the provision of a fixture structure in which the ring member 30 is split or divided and is so formed as to adapt the ends of the members of the ring to inter-engage and to be connected to each other and to the arm members of the fixture in such a manner that when assembled the 35 joints of the ring member are invisible thereby producing the same effect as the fixture in which the ring is made as an integral structure and which at the same time permits the parts of the fixture to be separated 40 so as to make it possible to place the entire fixture in a relatively small space for shipping, storing and other purposes, making it readily possible to assemble the parts of the fixture at the place at which the same 45 is to be used.

In carrying out the invention, therefore, the fixture ring to which the same more especially relates comprises a plurality of parts or members, each member being constructed 50 at one end to inter-engage with the adjacent end of the next ring member and in such a manner as to permit all the ring members to lie in substantially the same plane, while the inter-engaged ends of the 55 members of the ring are adapted to be con-

nected to one another and to the arm members of the fixture by a suitable coupling or other device to which the lighting elements of the fixture are attached. One end of each member of the divided ring is also 60 provided with an element, preferably an ornamental device, so connected thereto as to cover the joint between the ends of the members of the ring thereby making the joint 65 invisible and giving the ring the appearance of an integrally constructed member, all of which will be hereinafter more particularly described.

In the drawing:

Fig. 1 is an inverted plan and partial section of a lighting fixture in which my present invention is incorporated.

Fig. 2 is a plan of one end of a ring member.

Fig. 3 is a plan of the adjacent end of another ring member, and

Fig. 4 is a sectional elevation on the line 4—4, Fig. 1 illustrating the manner in which the ends of the members of the ring are connected to each other and to an arm of the 80 fixture.

Referring to the drawing, the split or divided ring member for a lighting fixture to which this invention particularly relates is made to comprise a plurality of sections 85 indicated respectively at 10, 11, and 12 to form a semi-circle or one-half of the ring, it being understood that the other portions of the ring are similarly constructed to complete the same. It is also to be understood 90 that the design shown in the drawing is merely illustrative as any suitable design may be employed, or in fact the ring may be made without any ornamental effect and still be within the spirit of the invention. 95

The number of the sections into which the ring is divided is also immaterial to the invention, but obviously is governed in any individual instance by the number of the arms employed in the fixture in which the ring is to be used. As illustrated in the drawing, therefore, there are six sections to the ring inasmuch as the fixture is provided with six arms. Irrespective, however, of the number of sections in the ring and whether it is made with an ornamental effect or in a plain manner one end of each section of the ring is provided with a recess 13 and shoulders 14 and 15. At this end of the ring also there is suitably connected 110

to one side thereof a cover member 16 which also may be made to represent a flower or a wreath or may be made in any other design to harmonize with the general design of the 5 ring and is secured in an offset position in any suitable manner to the obverse face of this end of the member of the ring. Centrally the ornamental cover member 16 is provided with an aperture 17.

10 The opposite end of each member of the ring is provided with a projection 18 and shoulders 19 and 20, together with an aperture or opening 21. As illustrated, the recess 13 is semi-circular and the edge of the 15 projection 18 is also semi-circular and adapted to fit within the recess 13 in such a manner that the shoulder 20 abuts against the shoulder 14 and the shoulder 19 abuts against the shoulder 15, in which position also the 20 aperture 21 is concentric with the aperture 17 and the bodies of these members of the ring are adapted to lie in the same plane, the obverse face of the member 11 lying flush against a portion of the reverse face of the 25 ornamental cover member 16.

As hereinbefore stated, the fixture comprises a plurality of arms, each of which is indicated at 22. At the end of each arm there is a socket 23 comprising a tapped 30 opening adapted to receive the stud or screw threaded end 24 of a coupling or other device 25. With the parts of the ring assembled as hereinbefore described, the screw threaded stud 24 is passed through the apertures or openings 17 and 21 and turned down into the tapped opening 23 so as to cause the end of the arm to bear against the reverse face of the ring member 11, and the arm at the end thereof is of sufficient diameter to 35 also engage a portion of the reverse face of the ring member 10, while the coupling 25 is preferably provided with a shoulder 26 adapted to engage the obverse face or a portion thereof of the ornamental cover member 16. This, as will be understood, connects the adjacent ends of the members of the ring and also secures the same in position 40 to the arms of the fixture.

It will be understood that the invention is 50 not limited to the particular manner as shown for the interengagement of the adjacent end of the members of the ring as other and equivalent constructions may be used without departing from the nature and 55 spirit of the invention.

I claim as my invention:

1. In a lighting fixture, a plurality of arms, a ring divided into a plurality of sections, with one end of each ring section 60 adapted to inter-engage with the end of the next adjacent section, a device attached to and extending beyond one end of each of the ring sections and adapted to conceal the joint between the same and the interengaging 65 end of the next adjacent section, and

means acting through the said device and with the inter-engaging end of the next adjacent section for simultaneously connecting these ends of the sections to one another and to an arm of the fixture. 70

2. In a lighting fixture, a plurality of fixture arms, a ring divided into a plurality of sections, each section comprising a flat member, with one end thereof adapted to interlock with the end of the next adjacent section, a device secured to one end of each of the ring sections and extending beyond the same for covering the joint made between the end to which the device is attached and the interlocking end of the next adjacent section 80 of the ring, and means acting through said device and the interlocking end of the next adjacent section for connecting the interlocking ends of adjacent sections to one another and simultaneously to an arm of 85 the lighting fixture so that the sections of the ring lie in substantially the same plane.

3. In a lighting fixture, a plurality of fixture arms, a ring divided into a plurality of relatively, flat sections, with one end of each section provided with a recess and shoulders and the opposite end of each section provided with a projection and shoulders so that when the sections of the ring are placed in position the projection at the 90 end of one section engages with the recess at the end of the next adjacent section and the shoulders at the ends of the sections abut against one another, a cover member secured to the end of each section in which the said recess is placed, there being an aperture in the said cover member and also in the end of each section in which the said projection is placed, the said apertures being in alignment when the ends of adjacent ring members are inter-engaged by the projection at the end of one member entering the recess at the end of the next member and the said shoulders abutting against one another, and means for connecting the ends of adjacent 95 sections together and simultaneously to an 100 arm of the fixture. 105

4. In a lighting fixture, a plurality of fixture arms, a ring divided into a plurality of relatively flat sections, with one end of each section provided with a recess and shoulders and the opposite end of each section provided with a projection and shoulders so that when the sections of the ring are placed 115 in position the projection at the end of one section engages with the recess at the end of the next adjacent section and the shoulders at the ends of the sections abut against one another, a cover member secured to the end of each section in which the said recess is placed, there being an aperture in the said cover member and also in the end of each section in which the said projection is placed, the said apertures being in alignment, when the ends of adjacent ring mem- 120 125 130

bers are inter-engaged by the projection at the end of one member entering the recess at the end of the next member and the said shoulders abutting against one another, and
5 a coupling member having a reduced end portion adapted to pass through the apertures in the ends of adjacent ring members

and to engage the end of an arm of the fixture to simultaneously connect the ring members together and to the arm of the 10 fixture.

Signed by me this 26th day of January, 1923.

ABRAHAM COOPER.
